J. M. GRAHAM,
LIGHT SIGNAL FOR ELEVATORS,
APPLICATION FILED JULY 22, 1907.

907,339.

Patented Dec. 22, 1908.

UNITED STATES PATENT OFFICE.

JAMES MONROE GRAHAM, OF NEW YORK, N. Y., ASSIGNOR, BY MESNE ASSIGNMENTS, TO ELEVATOR SUPPLY AND REPAIR COMPANY, A CORPORATION OF ILLINOIS.

LIGHT-SIGNAL FOR ELEVATORS.

No. 907,339.

Specification of Letters Patent.

Patented Dec. 22, 1908.

Application filed July 22, 1907. Serial No. 384,943.

To all whom it may concern:

Be it known that I, JAMES MONROE GRAHAM, citizen of the United States, residing at New York, in the county of New York and 5 State of New York, have invented certain new and useful Improvements in Light-Signals for Elevators, of which the following is a specification.

My invention relates to an elevator signaling apparatus, and my object is to provide a construction by which an intending passenger waiting at a floor may signal a car to stop and be informed which car is approaching him in the direction he wishes to go. In 15 such patents as Armstrong 499,411, Smalley & Reiners 634,220, and others, the "up" and "down" lights on the floors are arranged in front of each shaft, but the passenger must keep watch of them all, and, in cases 20 where the shafts are arranged on opposite sides of the hallway or in a long line, for example, he often loses a car because he has not observed the signal and consequently has not presented himself at the proper 25 shaft in time for the operator to see him.

In my invention I have provided "up" and "down" passenger's controllers, such as push-buttons, located on each floor, and "up" and "down" indicators at each floor 30 for each car, said indicators being grouped close together and adjacent said push-buttons, said indicators being arranged correspondingly to the location of the cars, and preferably numbered to correspond there- 35 with, so that the intending passenger need not watch all the shafts but merely the panel of indicators, and when a signal is displayed he will at once see it.

I have shown in connection with my in- 40 vention the electro-magnetic signaling mechanism invented by John D. Bowne of New York, and set forth in the United States patent issued April 16, 1907, No. 850,618, but any other suitable signaling apparatus 45 may be substituted.

In the drawings any floors of the building are referred to by numerals 1, 2 and 3, and the two elevators shown are designated 4 and 5. Slides 6 and 7 arranged in guides 8 50 and 9 are operated by suitable machinery in correspondence with the movements of the passenger cars, at reduced distance and speed of travel. Each car is provided with a cut-out switch 10 and car-signal light 11.

55 At some readily observed position near the

elevator shafts on each floor is placed a case 12, which contains an "up" pushbutton 13, and a "down" pushbutton 14, and a series of white lights 15 used to represent the ascending cars, and a like series of colored 60 lights 16 that indicate the descending cars. Each pair of lights comprising one white and one colored light is numbered in correspondence with one of the passenger cars, which bears the same number at its shaft 65 entrance, and on the car also if necessary.

Considering the drawing, it is assumed that a passenger has pressed the "up" pushbutton and that car 5, also designated by the Roman numerals II, has taken the signal. 70 Under those circumstances the slide 7 has made connection with the contact 17 and the fork 18 of the signaling mechanism has dropped, completing the circuit through the conductors 19 and 20 and lighting the second 75 white light in the lowest case 12 which is located on the first floor. At the same time, that is to say, before the passenger car has reached the floor, the circuit through the conductors 21 and 22 is also completed and the 80 elevator light 11 set glowing. Thus, the intending passenger after pushing the button sees directly in front of him a light informing him of the car he is to take, and the conductor is signaled to stop. The two signals, 85 one to the intending passenger and one to the conductor, are given before the car reaches the signaling floor, and sufficient time is allowed for the person to step to the proper shaft, and for the conductor to conveniently 90 bring his car to a stop.

If the person desired to go downwardly, he or she would press the down-signal pushbutton in the case 12, and the car 4 would take the signal at the contact 23, completing the 95 circuit through the conductors 24 and 25, and dropping the fork 26. The result would be to complete the circuit through the conductors 27 and 28, lighting the first colored light in the lowest case 12. The car-light 100 circuit would also be completed through the conductors 29 and 30, and the operation would be the same as explained for the "up" signal. Obviously, any number of elevators may be introduced and provided with indicating lights in the casings 12.

Having now described my invention and explained the mode of its operation, what I claim is—

1. In light signals for elevators, the combi- 105

nation with a plurality of elevators provided with car lights, of "up" and "down" signal pushbuttons, signal lights representing ascending and descending elevators and arranged in order adjacent to the said pushbuttons, and signaling means having circuits including the said pushbuttons, car lights and signal lights, substantially as described.

5 2. In light signals for elevators, the combination with a plurality of elevators provided with car lights, of "up" and "down" signal pushbuttons, pairs of different colored signal lights representing ascending and descending elevators and arranged in order adjacent to the said pushbuttons, and signaling means having circuits including the said pushbuttons, car lights and signal lights, substantially as described.

10 3. In light signals for elevators, the combination with a plurality of elevators provided with car lights, of "up" and "down" signal pushbuttons, signal lights representing ascending and descending elevators and arranged in order adjacent to the said pushbuttons, and signaling means constructed and arranged whereby the operation of a pushbutton enables the nearest car moving in the desired direction to take the signal, having circuits including the said pushbuttons, car lights and signal lights, substantially as described.

15 4. In light signals for elevators, the combination with a plurality of elevators provided with car lights, of a single pair of pushbuttons for each floor comprising an up-signal and a down-signal pushbutton, signal lights representing the ascending and descending elevators and arranged in order adjacent to the said pushbuttons, and signaling 20 means having circuits including the said car lights, pushbuttons, and signal lights.

5 5. In a signaling apparatus for elevators, in combination a plurality of cars and floors each floor being provided with an "up" and "down" passenger's-controller and "up" and "down" indicators for each car, each adapted to indicate one direction of movement of that car, said indicators being arranged close together and adjacent said passenger's-controllers, means for operating the indicators comprising said passenger's-controllers, and a commutator for each car operated correspondingly to the movement of its car adapted to operate its car's indicator on any floor only when a passenger's-controller on said floor has been operated and the car is approaching that floor in the direction corresponding to the controller operated.

10 6. In a signaling apparatus for elevators, in combination a plurality of cars and floors each floor being provided with an "up" and "down" passenger's-controller and "up" and "down" electrically-operated indicators for each car, each adapted to indicate one direction of movement of that car, said indicators being arranged close together and adjacent said passenger's-controllers, means for operating the indicators comprising said passenger's-controllers and a commutator for each car operated correspondingly to the movement of its car adapted to operate its car's indicator on any floor only when a passenger's-controller on said floor has been operated and the car is approaching that floor in the direction corresponding to the controller operated.

15 In testimony whereof I affix my signature in presence of two witnesses.

20 JAMES MONKOE GRAHAM.
